UNITED STATES PATENT OFFICE.

WILLIAM A. PARIS, OF EDGEWOOD PARK, PENNSYLVANIA, ASSIGNOR TO
WESTINGHOUSE ELECTRIC & MANUFACTURING COMPANY, A COR-
PORATION OF PENNSYLVANIA.

CONTROLLER FOR ELECTRIC MOTORS.

No. 807,858.

Specification of Letters Patent.

Patented Dec. 19, 1905.

Application filed April 8, 1905. Serial No. 263,644.

To all whom it may concern:

Be it known that I, WILLIAM A. PARIS, a citizen of the United States, and a resident of Edgewood Park, in the county of Allegheny and State of Pennsylvania, have invented a new and useful Improvement in Controllers for Electric Motors, (Case No. 1,445,) of which the following is a specification.

My invention relates to controllers for electric motors, and has special reference to controllers of the oil-immersed-drum type.

The object of my invention is to provide means which may be employed either for actuating the controller-drum or for lowering its inclosing casing at the will of the operator.

The use of an inclosing casing or tank for an oil-immersed controller-drum makes it advisable to provide a lowering means for said casing in order that the drums may be inspected. The devices heretofore employed for this purpose have been cumbersome and difficult of operation, and a special lowering-handle has generally been employed, whereas in the controller of my invention the drum-actuating handle is employed for lowering the inclosing tank.

My invention is illustrated in the accompanying drawings, in which—

Figure 1 is a longitudinal section, and Fig. 2 a plan view, of a controller with the cover removed to disclose the drum-actuating mechanism. Fig. 3 is a longitudinal section of the upper shaft-bearing and adjacent parts, and Figs. 4, 5, 6, 7, and 8 are sectional views of details.

In Figs. 1 to 8, inclusive, is illustrated a controller 113, comprising a base 114, a drum-actuating mechanism 115, a manually-operated controller-handle 116, a plurality of drums 117 and 118, a tank or casing 119, and a shaft 120. The drum-actuating mechanism 115 is supported from the main base 114 by a plurality of rods 121, 122, and 123 and comprises a spider 124, having a bearing 125 for the upper end of a shaft 126, which constitutes one section of the main shaft, the shaft 120 constituting the other section. The top plate 127 supports the shaft 120 in a bearing 129 and a sleeve 130, on which is cast a gear-wheel 131 and a cam-wheel 132. Attached to the plate 127 is a frame 133, to which the bearing-spider 124 and the supporting-rods 121, 122, and 123 are fastened. The lower

end of the shaft 120 is provided with a collar 134, which has a projection 135, that may engage with a notch 136 in the sleeve 130. The bottom surface of the collar 134 is provided with a projection 136^a, similar to the projection 135, which may engage with a notch 137 in a collar 138, that is similar to the collar 134, and is rigidly fastened to the upper end of the shaft 126. The sleeve 130 is fitted over collars 134 and 138, so that the shaft 120 is held in position and is so arranged that the collar 134 may engage either the collar 138 to actuate the shaft 126 or the notch 136 in the sleeve 130.

The position of the shaft 120 determines the engagement of the collar 134 and is itself dependent upon a binding-nut 139, which serves to hold the controller-handle 116 in position. When the nut 139 is set down against a shoulder 140 of the shaft 120, the projection 135 of collar 134 engages the notch 136 in sleeve 130; but when it is sufficiently raised from the shoulder 140 the projection 136^a of collar 134 drops down into engagement with the notch 137 in collar 138.

Under normal operating conditions the collar 134 is held in engagement with the sleeve 130 and the gear-wheel 131 on the sleeve 130 engages gear-wheels 141 and 142, which are keyed to the shafts of the controller-drums 117 and 118, respectively, that are rotatably supported upon an independent base 143, which is suspended from the spider-casting 124 by means of a plurality of rods or bars 144, 145, and 146. The controller-handle 116 is keyed to the shaft 120 by a taper pin 147, which is flattened on one side to engage a correspondingly-flattened portion 148 of the shaft 120.

A pawl 149 is pressed into engagement with the cam-wheel 132 by a spring 150 in the usual manner.

Substantially the entire length of the shaft 126 is screw-threaded to receive a correspondingly-threaded block 153, which is connected rigidly to a spider 154 by means of a tube 155, that is of sufficient internal diameter to slip over the shaft 120.

The spider 154 is fastened to a bottom plate 156 of the casing 119, and the length of the tube 155 is such that the upper edge of the casing 119 is seated in a groove 157 in the frame 133 when the block 153 is close to the

bearing 125. This arrangement provides a means for lowering the casing 119 when it is necessary to inspect the controller-drums. If the nut 139 is unscrewed, the collar 134 will drop into engagement with the collar 138, and the lower shaft 126 may then be rotated by the handle 116 to lower the tank 119 without any movement of the drum, since the collar 134 is not in engagement with the sleeve 130.

10 While I have shown and described a specific combination of devices for effecting a desired result, I desire it to be understood that all variations in form, dimensions, and arrangements of parts which do not materially change 15 the mode of operation or result are within the scope of my invention.

I claim as my invention—

1. In a controller, the combination with an inclosing casing and a contact-carrying member, of a handle for operating said member and means for disconnecting said handle and member and for operatively connecting the handle to the casing to lower and raise the same.

25 2. In a controller, the combination with an inclosing casing and a rotatable, contact-carrying member, of a two-part actuating-shaft and an operating-handle therefor, said handle engaging one part of said shaft to actuate 30 either said contact-carrying member or said inclosing casing.

3. In a controller, the combination with an inclosing casing and one or more rotatable, contact-carrying members, of a two-part actuating-shaft comprising an actuating portion and an operating-handle therefor, and a screw-threaded portion that may be engaged by said actuating portion to lower said inclosing casing.

40 4. In a controller, the combination with an inclosing casing and one or more rotatable, contact-carrying members, of a two-part actuating-shaft comprising an actuating portion and an operating-handle therefor, and a screw-threaded portion that may be engaged by said actuating portion to lower said inclosing casing, and a gear-carrying sleeve that may be driven by said actuating portion to drive said contact-carrying members.

50 5. In a controller, the combination with an inclosing casing and one or more rotatable contact-carrying members, of a two-part shaft comprising an actuating portion, and an operating-handle therefor, a collar on said portion that may engage either a screw-threaded portion of said shaft to lower said inclosing

casing or a gear-carrying sleeve to actuate said rotatable contact-carrying member.

6. In a controller, the combination with an inclosing casing and a rotatable contact-carrying member, of a subdivided actuating-shaft, comprising a driving portion and a threaded driven portion, an operating-handle fixed to said driving portion, a sleeve and threaded bushing rigidly attached to and actuated to 60 raise and lower said inclosing casing by said threaded driven shaft, and said driving portion being arranged to engage either said contact-carrying member or said threaded shaft when disengaged from said contact-carrying 65 member.

7. In a controller, the combination with an inclosing casing and a contact-carrying drum, of an operating-handle, a sleeve operatively connected to said drum, a screw-shaft operatively connected to said casing and a clutch device for connecting either the sleeve or the shaft to the operating-handle.

8. In a controller, the combination with an inclosing casing and a plurality of contact-carrying drums, of an operating-handle, a sleeve geared to said drums, a screw-shaft that engages a nut on said casing and a clutch device for connecting the sleeve to the operating-handle and disconnecting the shaft therefrom 85 or vice versa.

9. In a controller, the combination with one or more contact-carrying drums and a casing therefor having a centrally-located nut, of a screw-shaft that engages said nut, a rotatable 90 member that is operatively connected to said drum or drums, an operating-handle and a clutch device for operatively connecting said handle to either the screw-shaft or the drum-operating member and at the same time disconnecting the other part.

10. In a controller, the combination with one or more contact-carrying drums, an inclosing casing, a rotatable member geared to said drum or drums and a raising and lowering member 100 for said casing, of a single operating-handle and a clutch device for connecting said handle to the drum-actuating member and disconnecting it from the casing-actuating member or vice versa.

In testimony whereof I have hereunto subscribed my name this 30th day of March, 1905.

WILLIAM A. PARIS.
